CLAIM

The ornamental design for a clothes hanger, as shown and described.

DESCRIPTION

FIG. 1 is a front elevational view of a clothes hanger showing my new design, the rear elevational view being identical;

FIG. 2 is a top plan view thereof;

FIG. 3 is a bottom plan view thereof; and,

FIG. 4 is a side elevational view thereof, the opposite side elevational view being identical.

1 Claim, 1 Drawing Sheet

FIG. 2.

FIG. 1.

FIG. 3.

FIG. 4.
